UNITED STATES PATENT OFFICE.

GUSTAV H. MASSA, OF NEW YORK, N. Y., ASSIGNOR OF ONE-HALF TO
JOSEPH FAVREAU, OF SAME PLACE.

COMBINED GAME-COUNTER AND CARD-BOX.

SPECIFICATION forming part of Letters Patent No. 375,558, dated December 27, 1887.

Application filed April 6, 1887. Serial No. 233,888. (No model.)

To all whom it may concern:

Be it known that I, GUSTAV H. MASSA, of the city, county, and State of New York, have invented certain new and useful Improvements 5 in Combined Counters and Boxes for Cards and other Games; and I do hereby declare that the following is a full and exact description thereof, reference being had to the accompanying drawings, and to the letters of reference marked thereon, making a part of this specification, in which—

Figure 1 is a perspective view of my improved game-box provided with the new counting device; Fig. 2, a partial perspective of a 15 portion of a hinged double-leaf box, to which a modification of the invention is applied, showing the same opened out; and Fig. 3, a similar view of the inner side thereof.

My invention relates to devices for keeping 20 count of the points in games with cards, and for neatly stowing away the cards, pins, &c., employed in the game.

It consists in the construction and arrangement of a novel counting board or tablet and 25 its combination with a game-box, as is hereinafter more fully described, reference being had to the accompanying drawings, in which—

A represents a tablet or board made to constitute the top of a box or case, B, adapted to 30 receive neatly and confine properly the cards and the counting-pins when not in use.

The box or case B may be made in single 35 form and provided with a lateral opening, C, to be closed by a slide, D, as shown in Fig. 1, the interior of the case being subdivided by partitions E into suitable compartments to receive the cards, pins, &c.; or as an equivalent the box may be made in two equal divisions or leaves, F F, hinged together to admit of 40 being opened out and laid flat, so as to bring the outer faces of its divisions into the same horizontal plane, as shown in Fig. 2, the inner side of each division or leaf being subdivided into compartments G G, (see Fig. 3,) to receive the cards, and H to receive the pins. Each card-compartment G is provided with a transverse detachable retaining-plate, I, fitting at its ends into suitable grooves, m m, in the sides of the compartment. The pin-compartment 45 is closed by a sliding plate, J. A spring, K, (see dotted lines in Fig. 3,) may be fitted

in the bottom of each card-receptacle to hold the cards up against the retaining-plate I, whether there be many or few.

Each table consists of three rows, N O P, 55 of figures. The first, N, contains the nine units; the second, O, tens, from 10 to 90, and the third, P, hundreds, from 100 to 1000. Upon one side of each row of figures, and opposite each number in the row, pin-holes R R 60 are drilled in the board to receive counting-pins S, and an extra series of these pin-holes are drilled in a row, T, parallel with the row N of units, so as to bring a second hole in line with each unit upon the opposite side 65 thereof.

In addition to the four series of holes, in which each hole is designated by an approximate numeral, as aforesaid, four extra holes, W W W W, are provided to receive the four 70 counting-pins S S S S required for each table when said pins are not in play.

For a single-top box, A, where compactness is required, four of the counting-tables, constructed each of four rows of holes and three 75 rows, N O P, of numerals, are arranged in order upon the top of the box, as shown in Fig. 1, so that, beginning at the outer edge or margin on the left-hand side of the top of the box or at the left of each table and proceeding 80 inward, there is found, first, a row, T, of ten holes pierced at regular intervals apart, parallel with and close to said outer edge; second, the row or column N of nine units, one opposite each hole except the last; third, a 85 parallel row of holes, ten in number, in line with the first; fourth, a row or column, O, of tens, beginning with the number 10, opposite and in line with the number 1 of the row N of units and ending with 90, opposite the ninth 90 unit; fifth, a parallel row of holes, ten in number; sixth, a row or column, P, of ordinals, representing and progressing by hundreds, beginning with 100, opposite and in line with the numbers 1 and 10 of the column N and 95 O, and extending to 1000, opposite the last holes in the rows on either side of the column N of units, and, finally, another row of ten holes inside of the last column of ordinals.

The several columns or vertical rows of holes 100 and figures in the table are all parallel, and the horizontal rows of alternate holes and fig-

ures are likewise parallel, and four of the tables may be formed upon the top of the card-box, all as shown in Fig. 1.

As an equivalent modification of the device, 5 the two rows of holes to be designated by and corresponding with the row N of nine units may be arranged, respectively, in parallel lines across the top and bottom of the table, with the figures denoting the units placed along 10 side of the upper row. The ordinals for the tens, from 10 to 90, and the corresponding 15 nine holes are then arranged to extend at a right angle with said row N of units, with said ordinals extending in a vertical line under the figure 8 of the row of units N, and their corresponding holes extending in a parallel line on the right thereof under the unit 9, as shown in Fig. 2. The ordinals for the hundreds, 20 from 100 to 1000, are arranged to extend from the figure 1 at a right angle with the row of units N and parallel with the tens-row O, their corresponding holes being pierced outside of 25 said column of hundreds, parallel therewith and with the edge of the board, to intersect the row of holes formed across the bottom of 30 the table, as above described. In this modification of the invention the three rows of figures N O P, with their corresponding holes, thus form three sides of a parallelogram, whose fourth side is defined by the second extra row 35 of unit-holes, as shown in Fig. 2.

In the use of the invention three of the 40 four pins, S S' S'', supplied for each counting-table, are used to count and designate the 35 points made in the game by one of the players, and the fourth pin, S³, designates the number of games played. For example, one pin, S, is inserted step by step in the holes in one 45 of the rows corresponding to the column N, to designate the units, a second pin, S', is inserted in the holes corresponding to the tens column O, to designate the tens, and the third pin, S'', in the holes corresponding to the hundreds, while the pin S³ is inserted in the hole 45 in the row T, which is opposite the number in

the row of units corresponding with the number of games that have been played.

The pins are shown in the drawings so placed as to indicate four hundred and fifty-five points in the sixth game, as counted on the 50 table.

When the tables are not in use, the counting-pins are stored in one of the receptacles H within the box or case. The cards may likewise be packed away in its compartments 55 G G.

I claim as my invention—

1. The combination and arrangement, in a counting board or tablet, of three rows of ordinals marked on the board to designate, respectively, the units, from 1 to 9, in the first row, the tens, from 10 to 100, in the second row, and the hundreds, from 100 to 1000, in the third row, in combination with two rows 60 of ten holes each pierced severally in the board parallel with the second and third rows of figures, two rows of nine holes each pierced 65 severally in the board parallel with the row of units on each side thereof, and a series of counting-pins adapted to be inserted in said 70 several holes, all substantially in the manner and for the purpose herein set forth.

2. The combination, with a game-box for cards, of a top plate pierced with four rows 75 of holes, two of which correspond in number and are parallel with a row of units marked on the board, the third corresponds with and is parallel to a row of figures denoting the tens, from 10 to 90, inclusive, and the fourth corresponds with and is parallel to a row of 80 figures denoting the hundreds, from 100 to 1000, all substantially in the manner and for the purpose herein set forth.

In testimony whereof I have signed my name to this specification in the presence of two sub- 85 scribing witnesses.

G. H. MASSA.
